Primary Examiner—Prabhakar G. Deshmukh
Attorney, Agent, or Firm—Watts, Hoffmann, Fisher & Heinke[57] **CLAIM**

The ornamental design for a container, design as shown and described.

DESCRIPTION

FIG. 1 is a perspective view of a container showing my new design;

FIG. 2 is a typical side elevational view thereof;

FIG. 3 is a top plan view thereof;

FIG. 4 is a bottom plan view thereof;

FIG. 5 is a sectional elevational view taken along line 5—5 of FIG. 3;

FIG. 6 is a fragmentary sectional view taken along line 6—6 of FIG. 2;

FIG. 7 is a perspective view of a second embodiment of FIG. 1; and,

FIG. 8 is a perspective view of a third embodiment of FIG. 1.

The corresponding views disclosed in the second (FIG. 7) and third (FIG. 8) embodiments are similar to the first embodiment (FIGS. 2-6 inclusive) except the difference in proportions.
